UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM DOBBY.

Application filed July 5, 1927. Serial No. 203,417.

This invention relates to improvements in shedding mechanism for looms and more particularly to dobbies such as are used for weaving names in selvages.

5 My prior Patent No. 1,060,977 shows a dobby mechanism such as has gone into general use for the weaving of names in the selvages of cloth. The dobby shown in said patent is used in addition to the ordinary 10 shedding mechanism and operates with a multiplier which holds the name dobby inactive for a given number of picks, the dobby operating the required length of time to weave the selected name and then being inactive until the name is again to be woven.

A dobby made according to my aforesaid patent makes no provision for incorporating the warp threads controlled thereby into the cloth during the time that the name dobby 20 is idle and as a result these warps float from one name to the next and must be cut off before the cloth is ready for the market. It is the general object of my present invention to improve my former name dobby so 25 that the warp threads may be attached to the cloth between the names and thus avoid the necessity for trimming.

The dobby as set forth in the patent comprises a set of fingers which position upper 30 and lower hooks, these hooks being connected to the harness jacks by means of intermediate dobby back levers so that when either hook of a pair is moved outwardly the corresponding jack will be raised. It is 35 a further object of my invention to provide an auxiliary pattern surface which will act to control the hooks when the main cylinder of the dobby is inactive.

It is a still further object of my invention 40 to provide an auxiliary pattern surface made up of a plurality of disks having cam faces to operate the corresponding hooks and all of said disks being assembled for rotation in unison to cause the dobby to weave a regular 45 pattern between the names.

Inasmuch as the auxiliary surface and the main pattern surface both are able to control the hooks it is necessary to provide means whereby each pattern surface when at rest 50 shall not interfere with the control of the hooks by the other pattern surface. In the auxiliary surface I accomplish this result by so assembling the disks that a region of the pattern surface extending along its 55 length will be blank and this blank surface

will be presented to the auxiliary controls for the hooks when the main pattern surface is active.

With these and other objects in view which will appear as the description proceeds, my invention resides in the combination and arrangement of parts hereinafter described and set forth in the claims.

In the accompanying drawings, wherein I have shown a convenient embodiment of my invention,

Fig. 1 is a central vertical section through my improved dobby showing the parts in position for weaving names,

Fig. 2 is an end elevation looking in the direction of arrow 2, Fig. 1, said parts being shown in section for the sake of clearness,

Fig. 3 is a view showing parts of the structure looking in the direction of arrow 3, Fig. 2,

Fig. 4 is an enlarged vertical section on line 4—4 of Fig. 1,

Fig. 5 is a fragmentary enlarged detailed vertical section on line 5—5 of Fig. 1,

Figs. 6 and 7 are perspective views of the disks used for the auxiliary pattern surface,

Fig. 8 is a top plan view of a portion of a fabric showing a name in the selvage such as might be woven by the dobby,

Fig. 9 is a vertical section on line 9—9 of Fig. 8 showing the manner of attaching the warps forming the name to the fabric between names, and,

Fig. 10 is a diagram showing the arrangement of the cam faces on the auxiliary pattern surface.

Referring particularly to Figs. 1 and 2 it will be seen that I have provided a stand 10 which ordinarily is secured to the loom arch 11 in a position to locate the dobby over one of the selvages of the fabric being woven.

The dobby comprises a frame 12 on which is rotatably mounted a pattern cylinder 13 having a chain 14 preferably of the so-called double index type. A ratchet 15 is secured

to the shaft 16 to which the cylinder 13 is attached and provides means by which the chain and cylinder may be rotated. In order to actuate the cylinder there is provided a pawl 17 pivoted at 18 to a rocking arm 19

which receives an oscillation in the opposite direction on the next pick of the loom. Said pawl is provided with a shield 20 which cooperates with a controller 21, see Fig. 3, and during the normal rocking of arm 19 the

ratchet 17 will give an angular movement to the cylinder 13 every second pick of the loom when the controller is out of controlling position.

5 The means for determining the time in which the pawl 17 shall be active includes a lever 22 rocking about a fixed center 23 and having a depending finger 24 to cooperate with a multiplying mechanism. As shown 10 herein said mechanism comprises two multiplying chains 25 and 26, respectively, said chains being of different lengths and being formed of links of the form set forth in Figs. 2 and 3. Said chains are mounted on a cylinder 27 which is rigid with a ratchet 28 receiving periodic movements from a depending pawl 29 when the main chain is inactive and the cylinder 13 is at rest.

20 The chains 25 and 26 are each made up of high links and one low link and when both the low links come under the finger 24 the lever 22 will have a left hand movement as viewed in Fig. 3. At all other times during the rotation of said chains the high links on 25 one or both of said chains will hold the finger to the left as viewed in Fig. 3 and will therefore operate through the controller 21 to hold the pawl 17 out of operative position with respect to the ratchet which 30 drives the main cylinder and chain.

The pawl 29 which drives the multiplier chains 25 and 26 is controlled from the main chain 14 through a lever 30 pivoted to move about the fixed center 23. Said lever 30 has 35 a portion 31 to be raised by a clip 32 on the chain 14, the raising of said end 31 acting to move the arm 33 to the right as viewed in Fig. 3. Said arm 33 controls the position of the pawl 29 and when the arm is in the 40 position shown in Fig. 3 the pawl 29 will be operatively disposed with respect to the ratchet 28 which controls the multiplier chains 25 and 26. When clip 32 is not under the portion 31 spring 34 acts to pull the arm 33 to the left and thus to move the pawl 29 45 to the left. Said pawl is weighted as at 35 and the lower end thereof tends normally to move to the right as shown in Fig. 3 because of the weight 35.

50 The pattern chain 14 cooperates with dob- by fingers 36 and 37 which are raised and lowered by the pegs 38 on the chain when the cylinder 13 is rotating. The fingers 36 control lifter wires 39 which position an upper set of hooks 40 while the fingers 37 have direct contact with the lower set of hooks 41. Said hooks are pivoted in pairs to dob- by back levers 42 which in turn are pivoted to rocking levers 43 moving about a fixed 55 axis 44. Each rocking lever 43 has pivoted thereto a jack 45 the inwardly extending tail 46 of which lies under a pin 47 held in fixed position on the frame of the dobby. Said jacks are connected to cords 48 which 60 may pass through any suitable form of

guide 49 and extend down to the selvage or warp threads which are to be controlled by the dobby.

In order to give motion to the hooks there is provided a pair of reciprocating knife bars 70 50 and 51 located respectively on opposite sides of the shaft 52 on which the arm 19 rocks. Said knives may be formed rigid with the arm 19 and as the lever oscillates in the right hand direction bar 50 will have 75 a nonworking stroke to the right while bar 51 will have a working stroke to the left, and when said lever 19 oscillates in a left hand direction the upper bar 50 will have a working stroke to the left while the lower bar 51 80 will have its return or non-working stroke to the right. Said bars 50 and 51 are positioned to engage the hooks which are in low position and serve to move the dobby back levers 42 and consequently the jacks and harness cords according to the call of the main pattern surface 14 when the cylinder 13 is active. The matter thus far described may be the same as set forth in my aforesaid Patent No. 1,060,977. 90

As previously stated a dobby constructed as previously described makes no provision for weaving the warp threads into the selvage or other part of the cloth between the names and it is the principal object of my present invention to afford an auxiliary pattern surface which can be brought into action when the main pattern chain 14 is to come to rest after weaving the name. 95

Accordingly, in carrying my invention 100 into effect, I extend the frame 12 upwardly as shown clearly in Figs. 1 and 2 to provide supports 60 in which is rotatably mounted a shaft 61. Said shaft has secured thereto an actuator ratchet 62 by means of which the shaft may be given periodic angular motion 105 every second pick of the loom when the main chain is at rest. Mounted on that part of the shaft 61 which lies intermediate bearings 63 is a plurality of disks, said disks being of two forms, one of which is illustrated particularly at 64 in Fig. 6 as having a cam riser surface 65 and a plurality of openings 66 concentric with the central opening 67 through which the shaft 61 extends. The other form of disk is similar to that shown at 68 in Fig. 7 and has no riser cam portion 65, and disks 68 separating the cam disks. 110

115 The manner of securing the disks in fixed angular position on the shaft 61 is shown in Figs. 2 and 5. Each end of the auxiliary pattern surface is secured to the shaft 61 in the same manner, only one end being shown in section in the drawings. The shaft is provided with a key way 69 to receive a key 70 having a head 71, the heads entering a notch in the outermost disk 68^a adjacent the bearing 63. A rod 72 extends through the aligning openings 66 of disks 64 and openings 66^a of disks 68 and in this 120 125 130

way motion of the ratchet 62 is communicated to all of the disks on the shaft.

Said disks cooperate with a series of depressor levers 73 pivoted at 74 to an extension of the frame work of the dobby and said levers extend to the right as shown in Fig. 1 to have engagement with the upper ends of certain of the hook controlling wires. As shown more particularly in Figs. 1, 2 and 10 said levers 73 lie vertically over the ends of the lifter rods 39 which cooperate with fingers 36 to determine the position of the upper set of hooks 40. As shown particularly in Fig. 4 each lifter rod 39 extends upwardly from the fingers 36 and is offset as at 76 to form a support for one of the top hooks 40, the upper end of each rod 39 being bent back slightly so as to lie under the corresponding depressor lever 73. In this way 20 the levers 73 as well as the fingers 36 control the lifter wires and consequently the upper hooks 40. The relation of the lifter rods and spacer 79 is shown more clearly in Fig. 1 where it will be seen that retaining rods 80 and 82 serve to prevent accidental displacement of the rods. It is to be understood that there are as many top hooks 40 as there are depressor levers 73, there being one depressor lever and one cam disk 64 on the 25 shaft 61 for each upper hook 40.

A pawl 83 is pivoted on the stud 18 and is held against an adjusting screw 84 supported by the weighted end 35 of pawl 29 by a torsion spring 85 which surrounds the stud 18 as shown in Fig. 2. The screw 84 is so placed that the pawl 83 can actuate the ratchet 62 when the pawl 29 is in operative relation with the ratchet 28 and the pawl 17 is out of operative position with respect to the ratchet 15.

In assembling the disks on the shaft 61 it is possible to provide for several different weaves, but I have shown diagrammatically in Fig. 10 one particular arrangement which has operated successfully in actual practice. According to this arrangement twelve warp threads are controlled through a repeat of sixteen picks of the loom. The lines W represent the warp threads and the lines P indicate the picks of the loom, the lines W also representing the several cam disks. The cam portions C are indicated as located one on each line W, there being one disk for each warp thread, and in the particular draft shown herein there are two cams C for each alternate pick except one, namely that corresponding to the fourth pick of the repeat which has only one cam. The last of the alternate picks, indicated by line 55 —16— is blank and has no cams. The end view of the auxiliary pattern surface as shown clearly in Fig. 1 indicates this blank space extending along the length of the pattern surface as indicated at 86.

65 The depressor levers 73 are provided with

runs 87 which cooperate with the disk cams 64 and are depressed by the latter. Twelve cam disks are shown herein with their cam portions arranged as indicated in Fig. 10, and as the shaft 61 rotates the sheds will be 70 formed in the succession described, the warp threads being raised and lowered on the various picks. On the movement of the auxiliary surface for each repeat, however, the blank space 86 will come over the runs 87 75 and no shed will be formed.

A brief description of the operation of the device will illustrate the necessity of having the blank space 86 and will indicate also why a corresponding blank space must 80 be left on the main pattern surface. In operation, when the name is being woven, pawl 17 will move cylinder 13 every second pick of the loom so that a new bar on the pattern chain 14 will be brought under the 85 fingers 36 and 37 on alternate picks of the loom. Each chain bar is pegged so that during the weaving of the name the proper sheds will be formed to spell the name, but when the last pegged bar corresponding to 90 the last two picks in the name is reached a blank chain bar indicated at 88 in Fig. 1 will appear under the fingers. This blank bar comes under the dobby fingers 36 and 37 at the same time that clip 32 arrives under 95 lever 30 so that pawl 29 will be brought into action with respect to the multiplier by that stroke of pawl 17 which brings the blank bar 88 under the fingers. On the next downward stroke, therefore, without the loss 100 of a pick, pawl 29 will actuate the multiplier and pawl 83 acting through the ratchet 62 will impart an angular movement to the auxiliary pattern surface formed by the disks on shaft 61.

105 During the time that the fingers 36 and 37 are being raised and lowered by the pegs on the pattern chain 14 the blank space 86 on the auxiliary pattern surface will be over the runs 87 so that the depressor levers can move up and down without interfering with the action of the fingers and the hooks under the influence of the pegged part of the main dobby chain. When the bar 88 moves under the fingers to effect the change in the operation already described the auxiliary pattern surface will be free to control the hooks because of the fact that the fingers are not being acted upon by any pegs, bar 88 being unpegged as previously stated. On every 110 alternate pick of the loom after bar 88 comes under the fingers the disks will be given a new angular position to bring another set of the cam disks 65 into controlling position with respect to their corresponding depressor levers 73. The disks will continue to rotate so long as they are permitted to do so by the multiplier.

115 As described previously in connection with Fig. 3 when the pawl 17 is moved out 120 125 130

of action and pawl 29 operates to move the multiplier cylinder 27 the high links on the chains 25 and 26 will hold the shoe 24 of the lever 22 to the left as viewed in Fig. 5 3 and said shoe will be held in this position until the two low links on the chains 25 and 26 both appear under said shoe. While the shoe is being held raised by the high links of one or both of the chains the 10 clip 32 will be held under the lever 30 by reason of the fact that the pawl 17 for the main cylinder is inactive. When both low links come under the shoe 24, however, controller 21 will move to the left as viewed 15 in Fig. 3 and pawl 17 will fall into operative position with respect to the ratchet 15 so that on the next upward movement of the pawl 17 the clip 32 will be moved from under lever 30 and spring 34 will move the 20 pawl 29 away from the multiplier ratchet and will also move the pawl 83 away from the auxiliary pattern surface ratchet 62. The auxiliary surface will thereafter be inactive until again called.

25 In designing the auxiliary pattern surface and the two multiplier chains 25 and 26 it should be borne in mind that the multiplier should control the mechanism for a number of picks which is a multiple of the 30 number of angular spaces around the periphery of the auxiliary pattern surface. As shown herein eight movements of the auxiliary pattern surface are necessary to complete a revolution thereof, this motion 35 corresponding to sixteen picks and the multiplier chains 25 and 26 should therefore be of such lengths that their multiplying interval will be a multiple of sixteen picks. The chain 25, for instance, may have thirteen links while chain 26 may be provided with sixteen links, such a combination providing a multiplying interval corresponding 40 to 416 picks between names.

45 In Figs. 8 I have illustrated one name which can be woven by the dobby described herein, the name being indicated at 100 and the intervening space between names being designated at 101. As previously stated the warp threads 102 which form the name were required to float in the form of dobby set forth in my aforesaid patent, but by means of the structure set forth herein these warp threads can be attached to the fabric and made a part thereof by the auxiliary pattern surface. Each of the warp threads is connected to the fabric at regular intervals between the names at points 50 designated at 103 and these points may be arranged in any desired form, depending upon the arrangement of disks 64. Reference to Fig. 9 will show that the warp threads 102 float for a plurality of picks, fifteen as set forth herein and shown at 60 104, and then is woven into the fabric for 65 a single pick.

The warp threads are attached to the fabric by one pick only, and not two, as might be supposed from the fact that the depressor levers 73 and hooks 40 are held down for two picks. The reason for this 70 is that although the hooks are held down for two picks, yet the knives 50 and 51 require two picks to complete their movements. If knife 50 moves to the left immediately after a hook 40 falls the latter 75 will be drawn out on that pick but will be inactive on the following pick, and likewise, if the knife has a working stroke the pick after the hook falls, said hook is inactive on the first pick. Because of the 80 fact that the warps are raised for one pick only at a time they can scarcely be seen from the top of the fabric being woven, although being tightly bound thereto.

85 From the foregoing it will be seen that I have provided an improved form of name dobby wherein the warp threads controlled by the name dobby are incorporated into the fabric by the operation of an auxiliary pattern surface, each thread being woven 90 into the fabric at regular intervals. It is to be understood that other forms of the disks than that shown in Fig. 6 may be employed to give a greater or lesser number of picks to each revolution of the auxiliary 95 pattern surface and that the sequence in which the depressor levers 73 are actuated may be varied to give a limited variety of ways of weaving the warp threads into the selvage. While I have presented the invention as being a name dobby to control 100 selvage threads yet I do not wish to be limited to this application of the invention as the structure set forth herein may be employed to weave simple figures in the body 105 of the fabric and is not necessarily limited to the weaving of a name in the selvage.

Having thus described my invention it will be apparent that changes and modifications may be made therein by those 110 skilled in the art without departing from the spirit and scope of the invention and I do not wish to be limited to the details herein disclosed, but what I claim is:

1. In a pattern mechanism for operating 115 upon selected warp threads to be incorporated into a fabric, means operative at pre-determined times only to incorporate the selected threads into the fabric to form a figured pattern at spaced intervals, and auxiliary mechanism operative when the means are inoperative to attach the selected warp threads to the fabric at periodic points between the figured part of the fabric.

2. In a pattern mechanism for operating 120 upon selected warp threads to be woven into a fabric, a main pattern surface, means co-operating therewith to incorporate the threads into the fabric to produce a fancy pattern, mechanism to render said means 125 130

and main pattern mechanism inoperative, auxiliary pattern mechanism, and means co-operating therewith to attach each of the selected threads to the fabric at widely spaced points when the main pattern surface is inoperative.

3. In a pattern mechanism for operating upon selected warp threads to be woven into a fabric, a main pattern surface, means co-operating therewith to incorporate the warp threads into the fabric being woven to form a fancy pattern during the weaving of one portion of the fabric, an auxiliary pattern surface, and means co-operating therewith during the weaving of another portion of the fabric to attach the selected threads to the fabric at regularly spaced intervals.

4. In a pattern mechanism for operating upon selected warp threads to be woven into a fabric, a main pattern surface capable of producing a fancy weave, means co-operating therewith to incorporate the selected threads into the fabric to produce a fancy pattern during the weaving of a portion of the fabric, an auxiliary pattern surface, and mechanism co-operating therewith to incorporate each of the selected threads into the fabric at spaced intervals during the weaving of another portion of the fabric, whereby the selected threads will be attached to the fabric at a plurality of spaced points between the fancy patterns.

5. In a pattern mechanism for operating upon selected warp threads to be woven into a fabric, a main pattern cylinder, a removable pattern surface carried thereby and capable of change to produce a variety of fancy patterns, mechanism associated with the main pattern surface to incorporate the selected threads into the fabric during the weaving of a portion of the same to form a fancy pattern, auxiliary pattern mechanism remaining the same for all changes in the main pattern surface, and mechanism associated with the auxiliary pattern surface to attach each of the selected threads to the fabric at spaced intervals during the weaving of another portion of the fabric, whereby the threads are acted on to produce a fancy weave in one part of the fabric and are attached to the fabric at other parts thereof to prevent long floats.

6. In a pattern mechanism for operating upon selected warp threads to be woven into a fabric, a main pattern chain capable of change to produce a variety of fancy patterns, means co-operating therewith to incorporate the selected threads into the fabric during the weaving of a portion of the same to provide a fancy pattern, a cylindrical pattern surface completing its revolution in a predetermined number of picks, and mechanism associated with the cylinder to incorporate each selected thread into another

portion of the fabric once for each complete revolution of the auxiliary cylindrical surface.

7. In a pattern mechanism for operating upon selected warp threads to be woven into a fabric, a main pattern chain capable of change to produce a variety of fancy patterns, means controlled thereby to incorporate the selected threads into a portion of the fabric, an auxiliary pattern cylinder having a constant pattern surface irrespective of changes in the main pattern chain and completing its revolution in a predetermined number of picks, and mechanism co-operating with the auxiliary cylinder during the weaving of another portion of the fabric to incorporate each of the selected threads into the fabric once for each revolution of the auxiliary pattern cylinder.

8. In a pattern mechanism for operating upon selected warp threads to be woven into a fabric, a main pattern surface capable of producing a fancy pattern of any desired length, an auxiliary pattern surface completing its revolution always in the same number of predetermined picks, means to render said surfaces alternately operative to incorporate the threads into the fabric, the main pattern surface effective to cause the weaving of a fancy pattern by the selected warp threads and the auxiliary surface effective to incorporate each warp thread into the fabric at regular spaced intervals, whereby the selected threads are attached to the fabric at a plurality of spaced points between those portions of the fabric into which the threads are incorporated to produce a fancy pattern.

9. In a pattern mechanism for operating upon selected warp threads to be woven into a fabric, a main pattern surface to control the selected threads during the weaving of a portion of the fabric, and an auxiliary pattern surface to incorporate said threads into the fabric during the weaving of another portion of the same, said auxiliary pattern surface being formed of a plurality of flat disks each provided with a cam face, said disks being held together and the cam portions thereof lying at different points round the periphery of the pattern surface.

10. In a pattern mechanism for operating upon selected warp threads to be woven into a fabric, a main pattern surface effective to co-operate with the threads to incorporate the same into the fabric during the weaving of a portion of the latter to produce a fancy pattern, an auxiliary pattern surface effective to attach the warp threads to the fabric at spaced points during the weaving of another portion of the pattern, said auxiliary pattern surface comprising a plurality of disks arranged on a common axis to be rotated, each disk having a cam surface effec-

tive to produce a change in the position of the corresponding selected thread, the thread corresponding to the cam portion of each disk being incorporated into the fabric when 5 said cam portion reaches a predetermined point in the revolution of the auxiliary pattern surface.

11. In a pattern mechanism for operating upon selected warp threads to be woven into 10 a fabric, a main pattern surface effective to cooperate with the threads to incorporate the same into the fabric during the weaving of a portion of the latter to produce a fancy pattern, an auxiliary pattern surface effective to attach the warp threads to the fabric at spaced points during the weaving of another portion of the pattern, said auxiliary pattern surface including a plurality of disks arranged along a common axis, each disk 15 having a plurality of equally spaced openings therein concentric with the axis, a retaining rod to pass through one hole of each disk and hold said disks in fixed angular position, each disk having a cam portion effective to incorporate the corresponding thread into the fabric when the cam portion reaches a predetermined point in the revolution of the auxiliary pattern surface.

12. In a pattern mechanism for operating 30 upon selected warp threads to be woven into a fabric, a main pattern surface effective to incorporate the threads into a portion of the fabric to cause a fancy pattern, a multiplier element, an auxiliary pattern surface effective to incorporate each thread into the fabric at regular intervals during the weaving of another portion of the fabric, an oscillating member, and actuating members carried thereby for the main pattern surface, 35 the multiplying element and the auxiliary pattern surface, the actuating elements for the auxiliary pattern surface and the multiplier being alternately operative with the 40

driving mechanism for the main pattern surface.

13. In a pattern mechanism for operating upon selected warp threads to be woven into a fabric, a main pattern chain to incorporate the warp threads into a portion of the fabric to produce a fancy weave, an auxiliary pattern surface effective to incorporate each warp thread into another portion of the fabric at regular intervals, a multiplying element, and means to render said multiplying element and auxiliary pattern surface operative during the weaving of said other portion of the fabric while the main pattern chain is inactive, said means acting to cause the main pattern chain to be active with the auxiliary pattern surface and the multiplying element inactive during the weaving of the first-named portion of the fabric.

14. A pattern indicating element for controlling a loom shedding mechanism comprising a flat disk of uniform thickness having a central bore, a plurality of openings on a circle concentric with the bore, said element having a periphery the greater part of which is substantially circular, and an indicating cam formed with the element and having a face continuous with the said circular face.

15. A pattern indicating element for controlling a loom shedding mechanism comprising a flat disk of uniform thickness having a central bore, a plurality of openings on a circle concentric with the bore, said element having a periphery the greater part of which is substantially circular, and an indicating cam formed with the element and lying at a different radial distance from the axis of the bore than the remainder of the periphery of the element.

In testimony whereof I have hereunto affixed my signature.

ALBERT A. GORDON.
